United States Patent Office

Des. 231,780
Patented June 11, 1974

231,780

END PIECE FOR HANDRAIL

Edward C. Hallock, Summit, N.J., assignor to
Construction Specialties, Inc., Cranford, N.J.

Filed July 28, 1972, Ser. No. 276,225

Term of patent 14 years

Int. Cl. D25—02

U.S. Cl. D13—7

FIG. 1

FIG. 2

FIG. 1 is an underside perspective view of an end piece for a handrail incorporating my new design;

FIG. 2 is a front side perspective view thereof.

The back end of the end piece not shown is plain and flat.

I claim:

The ornamental design for an end piece for handrail, as shown and described.
